UNITED STATES PATENT OFFICE

90,509

DESIGN FOR A DOUGH PRODUCT

Angelo Ronzoni, New York, N. Y.

Application April 14, 1933. Serial No. 47,783

Term of patent 7 years

To all whom it may concern:

Be it known that I, ANGELO RONZONI, a citizen of the United States, residing at New York, in the county of Queens and State of New York, have invented a new, original, and ornamental Design for a Dough Product, of which the following is a specification, reference being had to the accompanying drawing, forming part thereof.

Fig. 1 is a top view of the product.
Fig. 2 is a side elevation of the product.
Fig. 3 is an end elevation of the product, and
Fig. 4 is a bottom view of the product.

I claim:

The ornamental design for a dough product,
as shown.

ANGELO RONZONI.
